METHOD OF MANUFACTURING ARTIFICIAL
SILK FILAMENTS

Harry Preston Bassett, Cynthiana, Ky., and
James Harold Torrence, Lincoln, Nebr., as-
signors, by mesne assignments, to Tubize Cha-
tillon Corporation, New York, N. Y., a corpora-
tion of Delaware

No Drawing. Application July 31, 1929
Serial No. 382,576

4 Claims. (Cl. 106—40)

Our invention relates to the manufacture of artificial silk filaments by a method in which fine particles of an inorganic pigment-like material are thoroughly incorporated with and dis-
tributed throughout the mass material of a solution of a cellulose compound preparatory to forming said material into an artificial silk filament by forcing it through a small orifice.

Broadly speaking, such process is described and claimed in U. S. patents of James A. Sing-
master, No. 1,725,742, granted August 20, 1929,
and No. 1,875,894, granted September 6, 1932.
In said patents the character of inorganic pig-
ment-like materials adapted for use and tending
to produce a filament of a desirable opacity, cov-
ering power and luster are set out and certain
methods are described for securing a thorough
distribution of the pigment-like particles in the
solution and produced filaments.

The object of our invention is to provide an
effective method for securing a thorough distri-
bution of the pigment-like particles in low vis-
cosity spinning solutions of cellulose compounds,
such, for example, as those found in the usual
processes of manufacturing artificial silk from
viscose and cuprammonium solutions, and in the
nitrocellulose and cellulose-acetate processes
when so-called wet-spinning methods are em-
ployed.

We have discovered that a very effective dis-
tribution of the pigment-like particles can be
secured and maintained in low viscosity cellu-
losic solutions by thoroughly mixing the pigment-
like material with a portion of the solution of
the cellulose compound in such manner as to
wet substantially all of the individual particles
with the solution and then introducing this mix-
ture into the bulk of the solution and mixing both
portions together. This mixture we have found
to be readily effected without such agitation of
the bulk of the solution as would tend to break
down its viscosity. Even in cellulosic solutions
of very low viscosity, the thorough distribution
thus obtained is maintained in the solution and
in the filaments spun therefrom. This embod-
iment of my invention therefore consists in the
method of mixing the pigment-like material with
a small portion of the cellulosic solution in such
manner as to thoroughly wet the particles and
this can best be effected by grinding the solution
and the particles together and then adding the
mixture thus prepared to the bulk of the cellulosic
solution and mixing the two solutions together.

By way of example, we mix titanium dioxide in
proportions of about one-half of one percent of

the mass material of the filament to be prepared
with a portion of, for example, a viscose solution,
say about five percent of the solution, in such
manner as to wet substantially all of the individ-
ual particles and then mix the pigmented portion
of the solution with the balance of the solution
to distribute the pigment-like particles through-
out the entire solution.

Having now described our invention, what we
claim as new and desire to secure by Letters
Patent, is:

1. The method of manufacturing artificial silk
filaments which comprises thoroughly mixing
pigment-like particles with a low viscosity cellu-
losic solution so as to wet substantially all of the
particles with the solution, mixing the mixture
so obtained with the bulk of the cellulosic solution
from which the filaments are to be spun,
whereby the pigment-like particles are incorpo-
rated in and widely distributed throughout the
cellulosic solution, and thereafter spinning said
solution to form artificial silk filaments.

2. The method of manufacturing artificial silk
filaments as set forth in claim 1, in which the
cellulosic solutions are viscose solutions.

3. The method of manufacturing artificial silk
filaments as set forth in claim 1, in which the
pigment-like particles are titanium dioxide.

4. The method of manufacturing artificial silk
filaments as set forth in claim 1, in which the
cellulosic solutions are viscose solutions and in
which the pigment-like particles are titanium
oxide.
